UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,330, dated November 18, 1890.

Application filed September 27, 1890. Serial No. 366,388. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

10 The leading feature of my design consists of flowers and leaves of the Japanese lily, the leaves and buds of the flower being arranged in a continuous scroll-like form over the surface of the paper and the flowers in full bloom protruding through the leaves, as represented 15 in the accompanying photograph.

The design is printed in any desired color upon tinted paper of any desired color.

What I claim is—

The design for wall-paper herein shown and 20 described.

Witness my hand this 13th day of September, 1890.

CHARLES BOOZE.
